UNITED STATES PATENT OFFICE.

HARRY W. McNAUGHT, OF INDIANAPOLIS, INDIANA.

RAILWAY SAFETY SYSTEM.

1,134,278.

Specification of Letters Patent. Patented Apr. 6, 1915.

Application filed April 3, 1913. Serial No. 758,591.

To all whom it may concern:

Be it known that I, HARRY W. McNAUGHT, a citizen of the United States, residing at Indianapolis, in the county of Marion and State of Indiana, have invented a new and useful Railway Safety System, of which the following is a specification.

It is the object of my invention to stop a car or train automatically in case the motorman or engineer over-runs a danger signal; and, further, to allow him to pass a danger signal provided he does so at less than a predetermined speed.

In carrying out my invention, I provide a member biased in one direction but held against movement in that direction by a pair of latches, one of which is released when the speed of the car or train exceeds a certain value and the other when an obstruction is encountered by a shoe carried by the car or train. When said member is released, it moves at a predetermined speed to cause both the application of the brakes and the shutting off of the power; or either, the shutting off of the power conveniently being accomplished by the admission of air pressure to a cylinder in which a piston is connected to the power-controlling lever. If such lever has a locking pawl, I provide a small cylinder and piston communicating with the first cylinder and piston for releasing said locking pawl.

The single figure of the accompanying drawing illustrates my invention semi-grammatically.

The car or train, of which but one wheel 10 is shown, is mounted to run on the tracks 11 in the usual manner, and at various points along the track there may be arranged semaphores or other signals 12 operated in any suitable manner, as through the connecting rod 13. Between or near the track rails 11, and at a suitable point relative to the semaphore 12, is a track shoe 15, connected by a pair of links 16 and levers 17 to a rod 18 connected through a lever 19 and link 20 to the same operating rod which controls the semaphore. Thus when the semaphore is moved, the track shoe 15 is also moved, this latter movement conveniently being vertical and the track shoe being raised when the semaphore

is moved to danger position. The track shoe 15 is guided in its vertical movement by a pair of pins 21 slideable in a suitable frame 55 22; and the links 16 and 17 are so arranged that they are cramped when the track shoe is raised.

The car or train (conveniently the motorman or engineer) carries a car shoe 25, the stem 26 of which is vertically movable in a guide frame 27. The stem 26 is connected to a latch lever 28, which normally engages a rod 29 to hold said rod against movement to the right. The rod 29 is biased to the right by a spring 30, conveniently mounted in a cylinder 31, the rod 29 being provided with a piston head 32 fitting in said cylinder and serving with the latter to form a dash-pot to retard the movement of the rod 70 29 to the right. The amount of retardation is controllable by a pet cock 33.

A suitably mounted shaft 35 is driven at a proportional speed with the wheel 10, as by being connected thereto by a belt 36 passing over the car axle 37 on which the wheel 10 is mounted and over a pulley 38 on the shaft 35. An annulus 39 is pivotally mounted on the shaft 35, and engages a finger 40 carried by a sleeve 41 slideable along the 80 shaft. Between flanges 42 on this sleeve 41 is a fork 43 or the end of a latch rod 44 pressed by a spring 45 into the path of a lug 46 on the rod 29, to prevent said rod from being moved to the right by the spring 85 30. When the speed of the car or train increases, the resultant increase in centrifugal force in the annulus 39 tends to move the latter into a plane more nearly at right angles to the shaft 35, such movement, when 90 sufficient, releasing the lug 46 from the latch rod 44.

The rod 29 is connected by a link 50, a bell-crank lever 51, and links 52 to valves 53 and 54, both of which are normally closed. 95 The valve 53 controls the air brakes, in the automatic air brake system connecting the air brake line to the atmosphere and in the straight air brake system connecting the air brake line to a source of air pressure. 100 Thus when the valve 53 is opened a setting of the brakes is obtained. The valve 54 when opened connects an air tank 55 to a cylinder 56, within which

is a piston 57 having a piston rod 58 connected to the power-controlling lever 59. The cylinder 56 may be pivotally mounted to take care of the side play due to the connection of the piston rod 58 to the power-controlling lever 59, in which case the air connection to the cylinder may be by a flexible pipe 56'. The power-controlling lever 59 may be provided with locking pawl 60 operating with a notched segment 61 but releasable therefrom by the lever 62 when the handle 63 of the power-controlling lever 59 is grasped by the operator. The piston 64 of a small cylinder 65 carried by the piston rod 58 is suitably connected to the locking pawl 60, the cylinder 65 being connected to the cylinder 56 by a longitudinal opening 66 in the piston rod 58. The cylinder 56 is provided with a pet cock 67, whereby the movement of the piston 57 to the right may be controllably retarded. It is also provided on the left-hand side of the piston 57 with a valve 68, which is normally open to allow the free reciprocation of the power-controlling lever 59 by hand but which closes automatically when air pressure from the tank 55 is admitted into the cylinder 56, the valve 68 being biased to open position, as by gravity, sufficiently strongly so that it is not closed by the pressure produced in the cylinder 56 by the manual operation of the piston 57.

In operation, the setting of the semaphore 12 to danger position raises the track shoe 15. If a car or train passes the semaphore 12, the car shoe 25 is lifted by the track shoe 15 and the rod 29 is thereby released from the latch lever 28. If at this time the car or train is exceeding a predetermined speed, so that by the action of centrifugal force on the annulus 29 the lug 46 is released from the latch rod 44, the unlatching of the latch lever 28 allows the spring 30 to move the rod 29 to the right, opening the valves 53 and 54. The opening of the valve 53 causes the application of the air brakes. The opening of the valve 54 admits pressure into the cylinder 56, which pressure immediately closes the valve 68. The air pressure from the cylinder 56 passes through the opening 66 into the cylinder 65, and by its action on the piston 64 withdraws the locking pawl 60 from the notched segment 61, whereupon the pressure within the cylinder 56, moves the piston 57, and through it the power-controlling lever 59, to the right to shut off the power. The shutting off of the power and the application of the brakes bring the car or train quickly to a stop. If the car or train is not exceeding a predetermined speed when the car shoe 25 engages the track shoe 15, the latch rod 44 by its engagement with the lug 46 prevents

the unlatching of the latch lever 28 from causing a movement of the rod 29 to the right, with its resultant setting of the brakes and shutting off of the power. After the rod 29 has been moved to the right, and the car or train brought to a stop, the motorman or engineer, by turning a handle 70 and thereby rotating a pinion 71 which meshes with rack teeth on the rod 29, may move said rod to the left to close the valves 53 and 54 and allow its relatching in its left hand position by the latch rod 44 and the latch lever 28. The handle 70 may be located in such a place that it requires the motorman or engineer to dismount from the car or train to operate it.

By omitting the latch lever 28 and its operating mechanism, the device may be used merely to prevent excessive speeds of the car or train. By omitting the latch rod 44 and its operating mechanism, the device may be used for stopping the car or train when it passes a danger signal, regardless of its speed.

If desired, either valve 53 or 54 may be omitted, in case it is desired that the device control either only the power or only the brakes.

I claim as my invention:

1. A safety device for track-traveling vehicles, comprising a member carried by the vehicle and biased in one direction, a pair of latches restraining it against movement in such direction, one of said latches being released when the vehicle exceeds a predetermined speed and the other being releasable by a controlling device along the track, and means operated by the movement of such member in the direction in which it is biased for causing the application of the brakes and the shutting off of the driving power. 105

2. A safety device for track-traveling vehicles, comprising a member carried by the vehicle and biased in one direction, a pair of latches restraining it against movement in such direction, one of said latches being released when the vehicle exceeds a predetermined speed and the other being releasable by a controlling device along the track, and means operated by the movement of such member in the direction in which it is biased for causing the shutting off the driving power. 110

3. A safety device for track-traveling vehicles, comprising a member carried by the vehicle and biased in one direction, a pair of latches restraining it against movement in such direction, one of said latches being released when the vehicle exceeds a predetermined speed and the other being releasable by a controlling device along the track, and means operated by the movement 125

of such member in the direction in which it is biased for causing the application of the brakes.

4. In a track-traveling vehicle, the combination of a power-controlling lever, a locking pawl for holding it in desired position, a cylinder and piston connected to said power-controlling lever so that relative movement between them actuates said lever, a second cylinder and piston associated with said locking pawl so that relative movement between them releases said pawl, said two cylinders being interconnected, and means controlled by the passage of the vehicle past a controlling device arranged along the track and by the speed of the vehicle for producing a difference in the pressures in each of said cylinders on opposite sides of the piston therein.

5. In a track-traveling vehicle, the combination of a power-controlling lever, a locking pawl for holding it in desired position, a cylinder and piston connected to said power-controlling lever so that relative movement between them actuates said lever, a second cylinder and piston associated with said locking pawl, so that relative movement between them releases said pawl, said two cylinders being interconnected, and means controlled by the speed of the vehicle for producing a difference in the pressures in each of said cylinders on opposite sides of the piston therein.

6. In a track-traveling vehicle, the combination of a power-controlling lever, a locking pawl for holding it in desired position, a cylinder and piston connected to said power-controlling lever so that relative movement between them actuates said lever, a second cylinder and piston associated with said locking pawl so that relative movement between them releases said pawl, said two cylinders being interconnected, and means controlled by the passage of the vehicle past a controlling device arranged along the track for producing a difference in the pressures in each of said cylinders on opposite sides of the piston therein.

7. In a track-traveling vehicle, the combination of a power-controlling lever, a locking pawl for holding it in desired position, a cylinder and piston connected to said power-controlling lever so that relative movement between them actuates said lever, a second cylinder and piston associated with said locking pawl so that relative movement between them releases said pawl, said two cylinders being interconnected, means controlled by the passage of the vehicle past a controlling device arranged along the track and by the speed of the vehicle for producing a difference in the pressures in each of said cylinders on opposite sides of the piston therein, and a valve associated with said

first cylinder and normally open to prevent such cylinder and its piston from interfering with the free manual operation of the power-controlling lever, said valve being automatically closed upon the operation of said last-named means.

8. In a track-traveling vehicle, the combination of a power-controlling lever, a locking pawl for holding it in desired position, a cylinder and piston connected to said power-controlling lever so that relative movement between them actuates said lever, a second cylinder and piston associated with said locking pawl so that relative movement between them releases said pawl, said two cylinders being interconnected, means controlled by the speed of the vehicle for producing a difference in the pressures in each of said cylinders on opposite sides of the piston therein, and a valve associated with said first cylinder and normally open to prevent such cylinder and its piston from interfering with the free manual operation of the power-controlling lever, said valve being automatically closed upon the operation of said last-named means.

9. In a track-traveling vehicle, the combination of a power-controlling lever, a locking pawl for holding it in desired position, a cylinder and piston connected to said power-controlling lever so that relative movement between them actuates said lever, a second cylinder and piston associated with said locking pawl so that relative movement between them releases said pawl, said two cylinders being interconnected, means controlled by the passage of the vehicle past a controlling device arranged along the track for producing a difference in the pressures in each of said cylinders on opposite sides of the piston therein, and a valve associated with said first cylinder and normally open to prevent such cylinder and its piston from interfering with the free manual operation of the power-controlling lever, said valve being automatically closed upon the operation of said last-named means.

10. A safety device for track-traveling vehicles, comprising a member carried by the vehicle and biased in one direction, a pair of latches restraining it against movement in such direction, one of said latches being released when the vehicle exceeds a predetermined speed and the other being releasable by a controlling device along the track, and means operated by the movement of such member in the direction in which it is biased for causing a reduction in the speed of the track-traveling vehicle.

11. A safety device for track-traveling vehicles, comprising a member carried by the vehicle and biased in one direction, and a pair of latches restraining it against move-

ment in such direction, one of said latches being released when the vehicle exceeds a predetermined speed and the other being releasable by a controlling device along the 8 track.

In witness whereof, I have hereunto set my hand at Indianapolis, Indiana, this eight-

eenth day of March, A. D. one thousand nine hundred and thirteen.

HARRY W. McNAUGHT.
